UNITED STATES PATENT OFFICE.

ARTHUR C. ROWE, OF NEW YORK, N. Y., ASSIGNOR TO A. C. ROWE & SON, OF NEW YORK, N. Y., A FIRM COMPOSED OF ARTHUR C. ROWE AND KENNETH P. ROWE.

FIRE-EXTINGUISHER.

1,076,787.

Specification of Letters Patent. Patented Oct. 28, 1913.

Application filed June 12, 1912. Serial No. 703,255.

To all whom it may concern:

Be it known that I, ARTHUR C. ROWE, a citizen of the United States, and a resident of the city, county, and State of New York, 5 (whose post-office address is 280 Broadway, New York city, New York,) have invented a new and useful Improvement in Fire-Extinguisher, which invention is fully set forth in the following specification.

10 The invention relates to hand-operated extinguishers for discharging carbon tetrachlorid or other fire extinguishing fluids.

The object of the invention is to provide a simple, compact, durable, and absolutely reliable apparatus, which will discharge a uniform and continuous stream when in use, and will prevent loss of its contents when not in use.

Broadly stated, the invention comprises a 20 chamber having a piston actuated by screw-pressure, so as to discharge with equal force all portions of the contents, from the first to the last.

The invention comprises also improved 25 means for sealing the contents against loss by leakage or evaporation.

The invention comprises further certain features of construction and arrangement to be hereinafter pointed out and claimed.

30 The invention will be best understood by reference to the annexed drawings that illustrate a preferred embodiment thereof.

In these drawings,—Figure 1 is a vertical section through one embodiment of my invention, shown as installed upon suitable brackets on a wall, and with its discharge-orifice sealed; Fig. 2 is a horizontal section through the line 2—2 of Fig. 1; Fig. 3 is a vertical section of the forward end of the 40 apparatus showing the discharge orifice as opened; and Fig. 4 is a vertical section through the upper end of the apparatus.

1 represents the chamber, preferably an elongated cylinder, closed at the rear (top) 45 by a centrally-apertured cap 2 threaded thereon, and at the front (bottom) by a corresponding centrally-apertured cap 3.

4 is a longitudinally disposed shaft carrying a thread of comparatively coarse 50 pitch, to constitute the feed-screw. One end of this shaft is journaled in the aperture through the upper cap 2, and is shown as carrying on its outer projection the hand-wheel 5. The other end of the shaft termi-

nates in a reduced portion with a cone-tip 6, 55 extending into the aperture in lower cap 3, and adjacent the outlet-orifice. The latter consists of a small bore through the plunger 7, which slides in the cap-aperture and in the bore of the nipple 8 that constitutes 60 a portion of the lower cap 3.

When not in use the apparatus may conveniently be suspended by means of a pair of upper brackets 9 and a pair of lower brackets 10, secured in convenient position 65 against a wall 11.

The piston is a compound one, comprising a screw-threaded nut engaging the feed-screw, and a piston proper carried yielding by the feed-nut. Where the chamber 70 is cylindrical, means are provided, such as an eccentrically-mounted disk, to prevent the nut turning axially with respect to the casing. The nut consists of the internally screw-threaded sleeve 12 (in which the feed- 75 screw turns) carrying the flange-plate 13.

14 is the centrally-apertured piston-plate having an externally-threaded lip around the aperture, and 15 is a packing-box ring engaging said lip, for inclosing a packing- 80 gland, the piston sliding freely but snugly over the sleeve 12.

16 represents guide-pins, riveted in the plate 14, and telescoping in guides in the plate 13. A coiled spring 17 surrounds each 85 guide-pin, tending to separate the plates 13 and 14.

18 is the washer, preferably a bag of asbestos containing glycerin, carried at the front (bottom) of the plate 14, as by means 90 of the plate 19 and screws 20; and preferably the outer rim of this bag is downturned as indicated in Fig. 1, the area of plate 19 being sufficiently reduced for that purpose. 95

21 represents a circular boss, located eccentrically at the rear (top) of the plate 13; and 22 is the eccentric disk journaled thereon. In this disk is the guide-slot 23 curved concentrically of its center of rotation (the 100 center of boss 21); and 24 is a guide-stud carried by the plate 13 and protruding into this slot. As stated, the casing 1 is preferably a cylinder, and the feed-screw 4 is preferably located centrally with respect 105 thereto, so that a circular nut or piston might be expected to rotate with the shaft 4 and turn freely in the cylindrical casing 1.

(without being advanced along the feed-screw). But, by means of the eccentric disk 22, this is prevented, and the nut and piston caused to advance. Upon rotating the feed-screw, the nut and its plate 13 tend to turn with it, but the eccentricity of the disk 22 prevents the latter from turning at all, while the nut (and its plate 13) soon turn the short distance sufficient to carry the stud 24 to the end of its slot 23,—whereupon the nut and the eccentric disk 22 become locked together, and thereafter the entire piston is propelled along the feed-screw,—thus forcing the fluid contents out of the chamber 15 under the tremendous screw-pressure thus provided. The feed-screw compresses the interposed springs 17, which latter transmit the pressure to the forward piston proper 14; and these springs store energy so as to 20 produce a continuous stream of uniform pressure, even though the operator (by continuously shifting his grip on the wheel) is intermittently turning the screw.

A nipple 25, screwed in the end of the 25 nipple 8, surrounds the plunger 7, to inclose a packing-gland. The rear (upper) end of the plunger is enlarged, and on the outside has longitudinal guide-grooves engaging the pins 27, to prevent it turning 30 axially; and on the interior has a circular recess screw-threaded to receive the end of the feed-screw 4, and terminating in a conical seat to receive the cone-point 6,—which latter is thus adapted to close the outlet- 35 orifice through the plunger.

In the position indicated in Fig. 3, the outlet-orifice is open, the point 6 being out of contact with its conical seat. In order to close the orifice, the plunger 7 is first shoved 40 inward, as by hand, until its internal screw-thread can engage the thread on the feed-screw, whereupon the latter is turned two or three revolutions, thus drawing the plunger inward until its conical seat engages the 45 tip 6 of the shaft 4, as seen in Fig. 1, which completely seals the outlet.

The apparatus is filled with carbon tetrachlorid or any other suitable fluid, through the opening that is closed by the screw-threaded plug 28. Preferably a small amount of glycerin may be introduced, which (owing to its lighter specific gravity) will rise to the top and form a film as 29; so that by maintaining the apparatus in the 55 vertical position indicated, vaporization of the tetrachlorid and possible escape past the plunger at the top, are prevented. As a further precaution, to prevent evaporation-loss at the upper end of the apparatus, and 60 to prevent the formation of a vacuum when the piston is advancing, I provide a thin plate or disk 30, of resilient metal, permanently concaved to provide the annular curve indicated in Fig. 4. This plate has a 65 central opening fitted around the collar 31

(of cork or rubber) located upon the stem of the shaft 4, while the outer edge thereof extends adjacent a similar ring 32 adjacent the casing 1. 33 is a vent-hole through the upper cap 2. When the piston is retracted (to the top of the apparatus), this curved plate 30 is somewhat flattened out against its natural tension, thereby forcing its inner and outer edges into the gaskets 31 and 32 respectively, and it may also be forced against the vent 33. As thus illustrated in Fig. 4, the top of the apparatus is completely sealed when not in use; but as soon as the feed-screw has been turned sufficiently to advance the nut, the natural resiliency of the plate 30 withdraws the edges thereof out of contact with the gaskets 31 and 32, thus permitting air to enter in the rear of the piston to prevent a vacuum.

In using the apparatus, it is taken from its brackets and pointed toward the conflagration, and the feed-screw rotated in the proper direction for advancing the piston; the first few revolutions force the plunger 7 90 downward, thus opening the outlet, the springs 17 yielding sufficiently to permit the screw to make a few rotations without advancing the piston proper (14—18) 95 against the non-compressible liquid; thereafter, further revolution of the hand-wheel in the same direction advances the piston and forces the contents through the outlet, a distance of thirty feet, more or less, in a continuous jet or stream.

I have thus described my invention at considerable detail, but only for the sake of clearness, since the invention is not limited to the precise construction and arrangement set forth. Modifications of construction 105 and of arrangement may be resorted to, the parts may be inverted or transposed, and some features used to the exclusion of others, without departing from the spirit of my invention.

Having thus described my invention, I claim:

1. A fire-extinguisher comprising a cylinder having an opening in its outer end, a hollow plunger keyed to slide snugly in said opening and interiorly screw-threaded at its inner end, a feed-screw extending longitudinally in said cylinder and adapted to engage said screw-threads when the plunger is forced rearward, a screw-threaded sleeve surrounding said feed-screw and carrying a flange-plate, a piston-plate telescoping upon said sleeve, springs interposed between said plates, a piston-washer carried upon said piston-plate, and a plate pivoted eccentrically upon said flange-plate for preventing said sleeve and piston from turning axially in said cylinder.

2. A fire-extinguisher comprising a chamber having an opening in its outer end, a

hollow plunger keyed to slide snugly in said opening and interiorly screw-threaded at its inner end, a feed-screw extending longitudinally in said chamber and adapted to engage said screw-threads when the plunger is forced rearward, a screw-threaded sleeve surrounding said feed-screw and carrying a flange-plate, a piston-plate telescoping upon said sleeve, springs interposed between 10 said plates, and a piston-washer carried upon said piston-plate.

3. A fire-extinguisher comprising a chamber, a piston fitted therein, a feed-screw for propelling said piston, a hollow plunger fitted in the forward end of said chamber and having a threaded seat in its inner end adapted to engage the extremity of said feed-screw whereby the outlet-orifice in said plunger may be forced against or away from 20 the end of said feed-screw.

4. A fire-extinguisher comprising a cylinder having an outlet-orifice, a feed-screw extending longitudinally in said cylinder, a nut traveling along said feed-screw, a piston carried yieldingly in front of said nut, and a disk mounted eccentrically upon said nut to prevent the latter from turning axially in said cylinder.

5. A fire-extinguisher comprising a cylinder having an outlet-orifice, a feed-screw extending longitudinally in said cylinder, a nut traveling along said feed-screw, a piston carried yieldingly in front of said nut,

and means to prevent said nut turning axially in said cylinder.

35

6. A fire-extinguisher comprising a chamber for containing a fire-extinguishing fluid and provided with an outlet, a hollow plunger sliding snugly in said outlet, mechanism for forcing said fluid out through the bore 40 of said plunger, and means actuated by said mechanism for sealing and unsealing said bore.

7. A fire-extinguisher comprising a chamber having an outlet-orifice, a feed-screw extending longitudinally in said chamber, a nut traveling along said feed-screw, and a piston carried yieldingly in front of said nut.

8. The combination with a fire-extinguisher comprising a chamber having a piston and means for advancing the latter, of a seal consisting of a transversely curved washer of resilient material located loosely in the rear of said piston and adapted to be 55 flattened by the piston in its rearward position to force the edges of said washer into contact with the walls of the chamber.

In testimony whereof I have signed this specification in the presence of two subscribing witnesses.

ARTHUR C. ROWE.
